[57] **CLAIM**

The ornamental design for frame bar of a stroller, as shown and described.

DESCRIPTION

FIG. 1 is a perspective view of frame bar of a stroller showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The frame bar of a stroller as shown in FIGS. 1 and 4-7 are broken away to show indeterminate length. The configuration shown in FIGS. 2 and 3 is consistent along the full length of the frame bar of a stroller.
